UNITED STATES PATENT OFFICE.

KARL KIEFER, OF CINCINNATI, OHIO.

DESIGN FOR A BOTTLE.

SPECIFICATION forming part of Design No. 35,558, dated January 7, 1902.

Application filed April 1, 1901. Serial No. 53,969. Term of patent 7 years.

To all whom it may concern:

Be it known that I, KARL KIEFER, a citizen of the United States, and a resident of Cincinnati, in the county of Hamilton, in the State of Ohio, have invented a new and original Design for Bottles, of which the following is a specification, reference being had to the accompanying drawings, showing the design.

Figure 1 is a view of my design for a bottle. Fig. 2 is a cross-section, being taken at the height of the line X X.

The leading feature of my design consists in the bottle being of a principally egg shape, having a truncated base and a plane and oval panel sunken into the side of the bottle in a vertical plane parallel to the bottle-axis. The top of the bottle narrows down to a vertical

neck, which is reinforced at the extreme end so as to form a lip, as commonly seen in bottles containing liquors.

A is an egg-shaped plane panel. It is somewhat sunken into the body of the bottle, which is visible in the cross-section, Fig. 2, and indicated by the two parallel oval lines circumscribing the panel in Fig. 1.

Having described my invention, what I do claim as new, and desire to secure by Letters Patent, is—

The design for the bottle herein shown and described.

KARL KIEFER.
